SOCKET ASSEMBLY FOR AIR-COOLED
TUBESElvin H. Potter, Collingswood, N. J., assignor to
Radio Corporation of America, a corporation of
Delaware

Application March 31, 1948, Serial No. 18,173

7 Claims. (Cl. 250—27.5)

1

This invention relates to improvements in supports for air-cooled electron tubes and has for its principal object to provide a rapidly detachable, substantially leak-proof, socket assembly of low electrical impedance for air-cooled electron tubes of the so-called "lighthouse" variety.

The invention will be described in connection with the accompanying drawing, wherein:

Fig. 1 is an elevational view of an air-cooled tube and socket assembly constructed in accordance with the principle of the invention.

Fig. 2 is an elevational view of the conduit portion of the assembly showing the manner in which the threaded base of the tube is supported upon a slidable sleeve-portion of the cooling conduit.

Fig. 3 is a sectional view taken on the line III—III of Fig. 1 showing two coupling devices within the slidable sleeve, one for connecting the sleeve to the conduit and the other for holding the tube in the sleeve.

Fig. 4 is an elevational view, partly in section, taken on the line IV—IV of Fig. 3 showing the interior of the sleeve and the manner in which the coupling devices of Fig. 3 operate, and

Fig. 5 is a view in perspective of the interior of the sleeve, with the tube removed, showing the contour of and relative arrangement of the coupling devices therein.

The electron tube T, to which the invention is here applied, is of the air-cooled lighthouse variety (JAN and RCA type No. 4C33) and is shown mounted, up-side-down, upon a tri-part supporting assembly which may here briefly be described as comprising: (a) an upper conduit, part C, which supplies current to the anode terminal 1 of the tube and a stream of air to its cooling jacket 2, (b) an intermediate annular pedestal, part P, upon which the flange-like grid connector 3 of the tube is resiliently supported and (c) a lower socket in the form of a transmission line, part L, through which electrical energy is supplied to the cathode cap 4 and filament prong 5 of the tube.

As is conventional in tubes of the type described, the cooling jacket 2 comprises a multiplicity of metal fins 2a which extend radially outward from the anode 6 (see Fig. 4) and are bent over adjacent to their outer ends into contact with the next adjacent fin to provide a multiplicity of open-ended channels 2c through which a cooling stream of air may be passed from the "base" of the tube to a region adjacent to the glass-to-metal seal 7 which joins the anode to the bulbous glass portion 8 from which the grid flange 3 projects. It will be observed that the

2

"upper" ends of the fins 2a all terminate in the same plane as the outer end of the internally-threaded anode terminal 1, i. e. in the plane of the "base" of the tube, as indicated by the reference line b—b in Fig. 4.

The conduit C which supplies current to the anode 6, and through which air flows to the cooling jacket 2, is here shown as comprising a horizontally disposed portion 10, which will be understood to be connected to a pump, not shown, and a shorter vertical section 11 which has a slidable sleeve 12 on its outer surface. The stationary pipe-like pieces 10 and 11 are rigidly secured to the underside of a stationary base 13 as by an insulating stud 14 disposed at the "elbow" of the pipe.

The dependent short arm 11 of the conduit C is provided with two vertically extending oppositely located bayonet slots 15, 15' which serve to accommodate a complementary bayonet pin 16 which is mounted, in a manner later described, within the vertically movable sleeve 12. Each of the bayonet slots 15, 15' terminates at its lower end in a laterally extending cut-out portion 17 within which the bayonet pin 16 is adapted to be seated upon rotation of the sleeve 12 while the sleeve is in its extended or "down" position. As is shown in Fig. 4, the lower corners of the bayonet slots which lie opposite to the lateral slot portions 17 are cut away as indicated at 17' in order to guide the bayonet pin 16 (and its support 18, later described) into the vertical portion 15 (15') of the said slots when it is desired to raise the sleeve 12 on the stationary vertical section 11 of the conduit.

As above mentioned, the sleeve 12 is supported for slidable or "telescopic" movement on and with respect to the stationary dependent part 11 of the air-supply conduit. When, as in the instant case, the said conduit has a horizontally extending part 10, that portion of the sleeve 12 which lies beneath the said horizontal part 10 may be cut away in a U-shape pattern, as shown at 12u (see Figs. 2 and 5), so that the said part 10 will not interfere with the upward movement of the sleeve 12.

As shown more clearly in Figs. 3, 4 and 5 the sleeve 12 contains a metal slab or plate 18 mounted with its major faces m arranged parallel to the vertical axis of the sleeve so that its presence will not appreciably impede the flow of air therethrough. The plate 18 is thin enough to be received within the vertical portion of the bayonet slots 15 in the dependent stationary part 11 of the conduit C and is soldered or otherwise rigidly

attached along its minor vertical faces *n* to the inner surface of the sleeve 12. The bayonet pin 16 is loosely fitted in a groove in the upper minor face of the plate 18 and is biased to bear upwardly therein by a pair of coil springs 19 contained in suitable holes on opposite sides of the vertical axis of the plate. The pin is retained in its groove by crimps 20 on the top edges of the groove. It will be observed upon inspection of Fig. 5 that, as indicated at 21 the corners of the plate 18 beneath the ends of the bayonet pin 16 are cut away to permit the pin to be depressed in its groove against the biasing force of the springs 19 when the sleeve is moved to a position whereat the ends of the bayonet pin are seated within the laterally extending portions 17 of the bayonet slot in the dependent stationary part 11 of the conduit.

An externally threaded stud 22 which is adapted to be received within the internally threaded anode terminal 1 serves to attach the tube T to the sleeve 12. It will be observed that when the tube is screwed-up on the said stud, the periphery of the cooling jacket 2 lies contiguous with the lower edge of the sleeve. In order to provide a substantially air-tight fit of low electrical impedance between these circular abutting edges of the cooling jacket and sleeve the stud 22 is somewhat loosely attached to the plate 18, as by a loosely fitting yoke 23 and screw 24, so that the tube may tilt slightly when it is screwed-up on the nut in any direction required to provide a "self-leveling" contact between the said abutting edges. Because of the inclusion in the mounting assembly of the pedestal P for the grid flange 3 of the tube it is apparent that the tube can be entered into the pedestal and screwed up on the stud 22 only when the sleeve is in its raised position, as shown in Fig. 2.

The pedestal P for the grid flange 3 of the tube T comprises a metal shelf 25 having a hole 25a therein of a diameter sufficiently large to permit the tube to be tilted therein and, suspended from the said shelf as on spacers 26, an apertured panel 27 containing a number of electrical contact elements in the form of spring fingers 28 arranged in circumferentially spaced relation about the periphery of the aperture in a position to engage the underside of the grid-flange 3. When, as is usually the case, the grid is operated at ground potential the terminals 28 may be connected to the metal shelf 25, or they may be insulated therefrom (as in the drawing) in the event that a D. C. bias is to be applied to the grid. It should be noted that the springs 19 which exert an upward biasing force on the bayonet pin 16 also exert a downward force upon the "upper" end of the cooling jacket 2 and this downwardly directed force is transmitted through the envelope of the tube to the grid flange 3 which is thus urged into intimate contact with the spring fingers 28.

The transmission line L in whose open-end the cathode cap 4 and filament terminal 5 are received terminates in a multiplicity of spring fingers 30 which grip the cap 4 tightly even though there may be minor inaccuracies in the alignment of the vertical axes of the transmission line L and the tube T resulting from tilting of the grid flange 3 upon its flexible supports 28. Such tiltable movement may be further compensated for by providing the vertically extending portion 31 of the outer conductor of the transmission line L with a bellows-like portion comprising a number of circular folds or pleats 32. The female

socket 33 for the filament prong 5 is free to slide on a flange 34 on the inner surface of the outer conductor and thus to compensate for any eccentricity in the relative alignment of the filament prong 5 with respect to the cathode cap 4.

From the foregoing it will be apparent that the invention provides a rapidly detachable, substantially leak-proof, socket assembly of low electrical impedance for air-cooled electron tubes, and one which lends itself readily for use in the mounting of electron tubes of the lighthouse variety.

What is claimed is:

1. A support for an electron tube of the type 15 provided with an anode terminal on one end, an open-ended cooling jacket adjacent to said end and a radially extending flange-like grid-like terminal intermediate said jacket and the other end of said tube, said support comprising a hollow sleeve to 20 which said tube is adapted to be removably secured with the leading end of said sleeve in contact with the periphery of said cooling jacket and the interior of said sleeve in flow communication with the interior of said cooling jacket, a stationary air-supply conduit upon which said sleeve is mounted for axial movement, a stationary pedestal mounted in spaced relation with respect to said conduit and sleeve and having an aperture therein through which said other end of 25 said tube is adapted to be passed when said sleeve is moved inwardly on said conduit and upon which said grid flange is adapted to be seated upon movement of said sleeve in the return direction.

2. The invention as set forth in claim 1 and 30 wherein spring means are mounted upon said pedestal for applying a biasing force to said grid flange in the direction of said stationary section of said conduit.

3. A support for an electron tube of the type 40 provided with an anode terminal on one end, a cooling jacket adjacent to said end and a radially extending flange-like grid terminal intermediate said jacket and the other end of said tube, said support comprising a hollow sleeve to which said tube is adapted to be removably secured with the leading end of said sleeve in contact with the periphery of said cooling jacket and the interior of said sleeve in flow communication with the interior of said cooling jacket, said sleeve containing a coupling member for said anode electrode and a bayonet pin; a stationary conduit section upon which said sleeve is adapted to be received and having an axially extending slot for 45 accommodating said bayonet pin upon movement 50 of said sleeve in the axial direction upon said conduit section, said slot terminating at the free end of said conduit section in a laterally extending portion within which said pin is adapted to be seated upon rotation of said sleeve on said conduit, a stationary pedestal mounted in spaced relation with respect to said end of said stationary conduit and having an aperture therein through which said other end of said tube is adapted to be passed when said sleeve is moved 55 in the direction of extension of said axial slot and upon which said grid flange is adapted to be seated upon movement of said sleeve in the return direction to a position whereat said bayonet pin 60 is received within said laterally extending portion of said bayonet slot.

4. The invention as set forth in claim 3 and 65 wherein said stationary conduit section and said sleeve are constituted of metal and comprise a 70 conductive lead through which electrical energy

may be applied to said anode terminal through the connector within said sleeve.

5. The invention as set forth in claim 3 and wherein spring means are housed within said sleeve for biasing said bayonet pin into intimate contact with an edge of said lateral extension of the bayonet slot in said conduit section.

6. The invention as set forth in claim 3 and wherein said anode-terminal connector is tiltably supported within said sleeve whereby when said 10

tube is connected to said connector the cooling jacket of said tube is "self-leveling" with respect to the adjacent edge of said sleeve.

7. The invention as set forth in claim 3 and 5 wherein resilient means are in register with said pedestal aperture for receiving and supporting said other end of said tube.
